UNITED STATES PATENT OFFICE.

WILLIAM H. GRISSOM, OF NEW YORK, N. Y.

DIE.

No. 928,256.

Specification of Letters Patent.

Patented July 20, 1909.

Application filed November 29, 1907. Serial No. 404,254.

To all whom it may concern:

Be it known that I, WILLIAM H. GRISSOM, a citizen of the United States, residing in the borough of Manhattan, city, county, and State of New York, have invented certain new and useful Improvements in Dies, of which the following is a specification.

My invention has for its object an improved die adapted particularly to cutting 10 mica-washers and the like.

In the drawings which show one of the forms which my improved die may take, Figure 1 is a mid-vertical section partly in elevation through devices within my invention; Fig. 2 is the same as Fig. 1, except that the section is taken through a vertical plane at right-angles to that in Fig. 1; and Fig. 3 is a plan view as seen from the line 3-3 in Fig. 1 looking in the direction of the 20 arrow with the upper right-hand portion of the parts in Fig. 1 broken away.

Describing now my improvements with particular reference to the devices of the drawings and reserving it to the claims to 25 point out the novel features, the devices shown comprise broadly speaking two sets of parts, the upper set adapted to be movable with the head of the machine and the lower stationary on the bed-plate. The 30 head and bed-plate or related parts of the machine have been omitted as constituting no part of the present invention.

In the first place describing what has been referred to, in view of the drawings, as the 35 upper set of parts, these comprise a hollow stem 1 adapted to be clamped or otherwise secured in any preferred manner to the head of the machine. Ordinarily said stem will be so secured with its axis vertical. In the 40 form of stem shown it is flanged outwardly at the bottom and said flange has a downwardly projecting internally screw-threaded rim 2. Screw-threaded into this rim is a cylindrical member 3 hereinafter referred to 45 as the upper-die, the periphery 4 of its bottom opening being a cutting edge. It will be noted that the upper-die shown has a seat 5 in its interior upon which rests or coacts the flange of a member 6, hereinafter spoken 50 of as the rejector protecting-plate or -member, which member below its flange has a portion of less diameter adapted to be received within the bottom opening through the upper-die. The rejector protecting- 55 plate is provided with a vertical hole through which the punch 7 next to be described can

work. The punch 7 comprises a lower portion, the periphery of whose free end has a cutting edge which may be about flush with the bottom of the upper-die. The upper 60 portion of the punch is adapted to be received into the hollow axis of the stem 1 and has an enlargement or shoulder 8 adapted to fit a corresponding recess in the stem and thereby form a stop preventing the punch 65 from being forced upwardly from below out of the stem. The punch is adapted to be fixedly secured to the stem by a set-screw 9 projecting through the wall of the stem and contacting with the periphery of the enlarged—or shoulder—portion of the punch. Surrounding the punch 7 within the upper-die 3 and located between the stem 1 and the rejector plate 6 is a thick-walled rubber-tube 10, hereinafter spoken of as the re- 75 ejector.

Describing now the lower set of parts, namely, those which ordinarily will be located stationarily on the bed-plate of the machine, these comprise a die-base 11 which 80 may take the rectangular plate-form shown. This die-base may be secured in any well-known manner to the bed-plate of the machine preferably so as to be adjustable in two directions under the upper set of parts al- 85 ready described. The die-base has a central vertical opening larger at the top than at the bottom to provide a seat 12 upon which the flange of the lower-die member 14 can rest. This lower-die 14 has its body portion located 90 within the vertical opening through the die-base and is secured in fixed position therein by bringing up on the set-screws 15 which project through the die-base from opposite ends thereof. The lower-die 14 is provided 95 with a central vertical opening 16 through it which preferably widens at its bottom as shown and has at its top a cutting periphery adapted to shear with the punch 7, the latter telescoping within it. Mounted to be capable of reciprocating motion to and from the die-base is a stripper-plate 17 having an opening through which to receive the upper or cutting portion of the lower-die and connected with the die-base by four bolts 18 in 100 the device shown. The ends of these bolts screw through from below into the stripper-plate, whereas their shanks near their heads have sliding fitting with vertical openings through the die-base, said openings being too 105 small to permit the heads of the bolts to pass. Surrounding these bolts between the die-

base and the stripper-plate are spiral springs 19. The result of the construction is that the stripper-plate can be pressed downwardly toward the die-base and so move below the 5 top of the lower die but when released will normally seek its former elevated position. To give uniformity and certainty to the elevation of the stripper-plate so that it will surely return to its original position instead 10 of to some position short thereof, I provide a rubber ring 20 interposed between the die-base and the stripper-plate.

The operation of the described devices will now be understood. In Fig. 1, the devices 15 are shown positioned as they will be when the upper set of parts is elevated. A piece of mica 21 having been inserted, the downward stroke of the die-head cuts the washer complete and in doing so positions the parts 20 as shown in Fig. 2, the mica washer being shown in section at 22.

It will be noted from Fig. 2 that the rejector protecting-plate 6 has been forced back above its normal position, which is 25 about-flush with the cutting edges of the upper-die and punch, and that its place has been taken up by the washer 22 which has just been cut and the top of the lower-die. The rejector protecting-plate in thus being 30 forced to recede has strongly compressed the rubber rejector 10. Similarly the stripper-plate 17 has been forced below its normal position which is with its top about flush with the cutting-edges of the lower die and in 35 so doing has strongly compressed the rubber and springs located between it and the die-base. The washer having been thus formed complete by the downward stroke of the die-head, its upward stroke permits the release of all of the parts into the position 40 shown in Fig. 1 under the restorative action of the rejector devices above and below. The result is that the washer is pressed downward and the stock upward into the original 45 plane which they occupied when fed into the machine at Fig. 1. In most cases the washer is placed back into the very hole in the stock out of which it was cut. The center blank out of the washer falls through the opening 50 in the lower-die.

I have found that to make the rejector invariably reject all washers irrespective of the thickness of the stock, it must have considerable initial compression which is another 55 way of saying that the piece of rubber comprising the rejector must have a length considerably longer than the vertical clearance in the die. This means that if a die were to be used without the plate 6 but using a 60 length of rubber within the die sufficient to reject thick mica, it would necessarily project so far below the cutting edge of the die that it would make the device practically inoperative and would be forced between the 65 cutting edges and soon destroyed. There-

fore it is seen that the protecting-plate 6 has in addition to its function of protecting the lower-end of the rubber rejector from cutting, the even more important function of permitting the rejector to be put under an 70 initial compression sufficient to make it reject all thicknesses of washers, and which initial compression is such that it is impracticable or at least prohibitive to obtain it by merely permitting the rubber to project 75 without using any plate 6. Therefore the vital importance of the plate 6 in connection with the rubber rejector will be better appreciated.

The devices have been specially designed 80 to make same readily adjustable to cut washers of various inside and outside diameters by a simple change of cutting tools. Thus, to vary the size of the hole in the washer it is only necessary to unscrew the 85 upper-die 3, loosen the set-screws 9 and remove the inner punch 7 and then to replace it by a punch of larger or smaller cutting diameter, of which there may be a set for use in connection with each machine. Of course 90 as the upper punch 7 is changed it will be necessary to correspondingly change the lower-die 12 which is effected in an equally simple manner by removing the stripper-plate 17, loosening up on the set-screws 15 95 and removing and replacing the lower-die 14. Similarly the upper-die 3 can be replaced by others in obvious manner. The same feature of interchangeability in the devices shown 100 will of course be found equally advantageous when replacing worn tools with new ones of the same size.

The rubber 20 and not the springs 18 is depended upon for the rejector action of the stripper-plate 17, the purpose of the springs 105 18 being rather to prevent one corner of the plate from lagging behind the others in its motion to and from the die base. In other words, the springs 18 make the stripper-plate move more evenly and with less friction 110 than it would in their absence.

Having thus described my invention, what I claim is:

1. In a mica-punching device, the combination of a hollow stem; a punch adapted to be supported in the hollow of the stem and having a shoulder received against a seat therein and adapted to be secured fixedly in such position by a set-screw through the wall of the stem; a die comprising a hollow member screw-connecting with the stem to receive the punch through its interior with the cutting edge of the latter separated by an annular space from the cutting edge of the die; a plate supported loosely in said annular 115 space; a rubber tube about the punch within the die and bearing on said plate; and means adapted to shear with said punch and die. 120

2. In a mica-punching device, the combination of a die-base having a vertical opening 130

through it with an upward-facing seat; a die adapted to be received within said opening and having a flange resting on said seat, and adapted to be secured fixedly in such position by set screws through the die-base; a stripper-plate connected with the die-base to be capable of motion to and from it and having an opening through which projects the cutting edge of the die; resilient rubber located between the die-base and the stripper-plate; and means adapted to shear with said die.

3. In a mica-punching device, the combination of a hollow stem; a punch adapted to be supported in the hollow of the stem and having a shoulder received against a seat therein; means adapted to secure the punch in position in the hollow stem; a die comprising a hollow member screw-connecting with the stem to receive the punch through its interior with the cutting edge of the latter separated by an annular space from the cutting edge of the die; a plate supported loosely in said annular space; a rubber tube about the punch within the die and bearing on said plate; and means adapted to shear with said punch and die.

4. In a mica-punching device, the combination of a die-base, having a vertical opening through it with an upward-facing seat; a die adapted to be received within said opening and having a flange resting on said seat; means adapted to secure the die within the opening in the die-base; a stripper-plate connecting with the die-base to be capable of motion to and from it and having an opening through which projects the cutting edge of the die; resilient rubber located between the die-base and the stripper-plate; and means adapted to shear with said die.

5. In a mica-punching device, the combination of a die, a co-acting punch and a rejector comprising resilient rubber located to be put under compression by the punching operation, and plate-protected from being sheared, the rejector operating on the stock through its plate-protection.

In witness whereof, I have signed my name to the foregoing specification in the presence of two subscribing witnesses.

WILLIAM H. GRISSOM.
